Specification for Design.

Patented Aug. 25, 1914.

Application filed July 18, 1914. Serial No. 851,833. Term of patent 7 years.

To all whom it may concern:

Be it known that I, JOHN J. NASH, a citizen of the United States, residing in Waterbury, in the county of New Haven and State of Connecticut, have invented a new, original, and ornamental Design for Bed-Trimming, of which the following is a specification, when taken in connection with the accompanying drawing.

In the drawing, Figure 1 is a side eleva-

tion of bed trimming embodying my design; and Fig. 2 is a top plan view of the same.

What I claim is:—

The ornamental design for bed trimming, substantially as shown.

JOHN J. NASH.
